UNITED STATES PATENT OFFICE.

FREELAND C. SNEDEN, OF GRAND RAPIDS, MICHIGAN, ASSIGNOR OF ONE-HALF TO CHRISTOPHER M. KELLY, OF GRAND RAPIDS, MICHIGAN.

FASTENER FOR SLATE ROOFS.

SPECIFICATION forming part of Letters Patent No. 718,165, dated January 13, 1903.

Application filed March 24, 1902. Serial No. 99,652. (No model.)

To all whom it may concern:

Be it known that I, FREELAND C. SNEDEN, a citizen of the United States, residing at Grand Rapids, in the county of Kent and State 5 of Michigan, have invented certain new and useful Improvements in Fasteners for Slate Roofs; and I do hereby declare the following to be a full, clear, and exact description of the invention, such as will enable others skilled 10 in the art to which it appertains to make and use the same.

My invention relates to improvements in fasteners for slate roofs; and its object is to reduce the risk of breakage of the slates, to 15 provide means whereby the roof may be readily repaired, to provide a cheap and practical device, and to provide the same with certain useful and new features hereinafter more fully described, and particularly pointed out 20 in the claims.

My invention consists, essentially, in a device made of wire and adapted to yieldingly hold the slates in place and from which the 25 respective slates may be readily detached, as will more fully appear by reference to the accompanying drawings, in which—

Figure 1 is a plan of a portion of a slate roof secured by my improved device; Fig. 2, an edge view of the same; Fig. 3, a detail of the 30 fastener used in the body of the roof; Fig. 4, a fastener for the half-slate on the edge of the roof; Fig. 5, a bottom fastener used at the eaves of the roof; Fig. 6, an edge-fastener for the roof, and Fig. 7 a section on the line 7 7 35 of Fig. 1.

Like letters refer to like parts in all the figures.

A represents the roofing-boards upon which the slates are laid, B full-size slates, and B' 40 half-size slates on the margin of the roof.

Throughout the body of the roof each slate is secured by a fastener, (represented in Fig. 3,) consisting of outwardly curved and diverging arms C C, of flattened wire, having 45 hooks D D at the lower ends to engage the lower ends of the respective slate under which it is placed. These arms join at E and are twisted together and bent downward a sufficient distance to extend to the roofing-board 50 and thence extend upward along the surface

of the roofing-board in outwardly diverged and curved portions F F, which are joined at their upper ends and turned downward, being twisted together, as at G, to form a screw-threaded portion to be driven into the roofing-board to securely hold the fastener in place. These fasteners (shown in Fig. 3) are arranged relative to four slates as follows: The upper slate directly above the fastener rests on the arms C C and is engaged at the 60 lower end with the hooks D. The next two slates below this are arranged on each side of the portion E and with their edges close to the same and extend beneath the arms C C and are each held at their lower ends by similar fasteners. The fourth slate extends upward beneath these two side slates and in line with the first-named slate, and its upper end extends to a sufficient distance below the portion E of the fastener to provide clearance 70 enough to slide it upward a sufficient distance to be released from the hooks D D of its respective fastener. These slates are thus securely held from moving either laterally or downward and at the same time are yieldingly held in place by spring-pressure, so that 75 there is no risk of breakage from vertical strain of frost or otherwise, and, furthermore, the arms C C separate the slates a slight distance from each other sufficient to prevent 80 water from being drawn upward between the slates by capillary attraction, thus making leakage or freezing between the slates. This separation of the slates also affords ventilation throughout the roof, which is desirable. 85

It will also be observed that any one slate can be readily detached and another inserted in its place by simply sliding the slate upward sufficient to release the slate from the hooks D D of its fastener. It can then be sprung 90 outward, by reason of the yielding character of the fastener, enough to slide down and out above the hooks D D. Another slate can now be inserted in its place by sliding the same over the hooks until it passes the same and 95 then lowered to place in the hooks.

Fig. 4 represents what might be termed a "half-fastener," substantially the same in character as the one described. It is provided with a single arm C', having a hook D' and 100

a vertical extension E', and is thence extended laterally at F' to pass inward along the roofing-board and then bent downward at G' to be inserted in the same. The portion F' 5 yields by torsion and forms a spring, the same as the part F heretofore described. This fastener is used to support the half-slates B' at the margin of the roof. Fig. 6 shows a margin-hook to further secure the slates at the 10 margin of the roof, consisting of a straight flattened portion C'' to extend inward along the surface of the roof-board and having an upwardly-turned hook D'' at its outer end to engage the edge of the slates and a downwardly-turned inner end G'' to be inserted 15 in the roofing-boards. The edges of the slates at the eaves are supported by a device shown in Fig. 5, which is similar to that shown in Fig. 3, except the parts E and F are omitted, 20 the portions G'' being inserted in the roofing-boards and the arm C'' extending beneath the slates and along the surface of the roofing-board and the hooks D'' at the lower end engaged with the lower ends of the slates to 25 keep the same from sliding downward. In attaching these devices as shown in Figs. 3 and 4 to the roofing-boards the ends having the hooks D are placed in contact with the roofing-boards, and the portions G to be inserted 30 in the roof are turned at an acute angle with the arm C, whereby they are placed vertically to the roof-board and then forced into the same. There is thus a slight tension upon the device whereby the arms C are yield- 35 ingly pressed toward the roofing-boards by the flexible character of the portions F or F'. I prefer to flatten only the portions of the wire comprising the arms C and hooks D, the remainder of the wire being left round.

40 Having thus fully described my invention, what I claim, and desire to secure by Letters Patent, is—

1. A wire fastener for roofing-slates distinguished by a flattened laterally-curved and 45 flexible portion to extend beneath the slate, a hook at the lower end to engage the lower edge of the slate, and a downwardly-bent upper end to insert in the roof-board.
2. A fastener for roofing-slates, having di- 50 verging arms provided with hooks at their lower ends, and joined at their upper ends and having a downward extension at substantially right angles to the arms and adapted to be inserted in the roofing-boards, substan- 55 tially as described.
3. A fastener for roofing-slates, consisting of wires having ends twisted together and adapted to be inserted in the roofing-boards and diverging arms extended substantially at 60 right angles to the twisted portion and pro-

vided with hooks at the other ends, substan- 65 tially as described.

4. A fastener for roofing-slates, consisting of two wires twisted together at one end, and having diverging outwardly-curved and flat- 65 tened arms extended at substantially right angles to the twisted ends, and provided with hooks at their other ends, substantially as described.

5. An edge-fastener for roofing-slates con- 70 sisting of a wire having a hook at one end, a downwardly-extended portion to engage the edges of the slates, an inwardly-turned portion to extend beneath the slates, and a downwardly-turned portion to be inserted in the 75 roof-boards, substantially as described.

6. An edge-fastener for roofing-slates, con- 70 sisting of an inward-curved and flattened arm having a hook at its lower end, a down- 80 ward extension at the upper end of the arm to engage the edge of the slate, an inward ex- 85 tension to pass beneath the slates, and a down- 90 ward extension to be inserted in the roof- boards, substantially as described.

7. A fastener for roofing-slates consisting 85 of diverging arms having hooks at their lower ends and joined at their upper ends, a down- 90 ward extension at the upper end of the arms to pass between the respective side slates, a flexible portion to extend upward along the 95 surface of the roofing-boards and a downward- 100 extended portion to be inserted in the roof- ing-boards, substantially as described.

8. A fastener for roofing-slates consisting of two wires having hooks at their lower ends, 95 joined and twisted at their upper ends and extended downward to pass between the side slates, and also having outwardly-curved and 100 flexible portions to extend upward along the surface of the roofing-boards, and having their upper ends twisted together and adapt- 105 ed to be inserted in the roofing-boards, sub- 110 stantly as described.

9. A fastener for roofing-boards consisting of diverging and outwardly-curved flattened 105 wire arms having hooks at their lower ends, said wires also twisted together at their up- 110 per ends and extended downward to pass be- 115 tween the side slates, and thence extended upward in outwardly-curved portions, hav- 120 ing their upper ends joined and twisted to- 125 gether and bent downward at an acute angle, substan- 130 tially as described.

In testimony whereof I affix my signature in presence of two witnesses.
